Inventor
Jere L. Wentz
By his Attorney
Andrew J. Murphy

UNITED STATES PATENT OFFICE.

JERE L. WENTZ, OF PASSAIC, NEW JERSEY.

CONVEYER.

Application filed January 6, 1920. Serial No. 349,833.

To all whom it may concern:

Be it known that I, JERE L. WENTZ, a citizen of the United States, residing at the city of Passaic, in the county of Passaic and 5 State of New Jersey, have invented certain new and useful Improvements in Conveyers, of which the following is a specification.

My invention relates to improvements in conveyers and the object of my invention is 10. to provide a simple and convenient device of the character described.

I accomplish this object by the device illustrated in the accompanying drawings, in which—

15 Figure 1 is a plan view of the device

Figure 2 is a side view of the device inverted, and

Figure 3 is a section of the device on the line 3—3 in Figure 1.

20 Similar characters refer to similar parts throughout the several views.

In a frame comprising a plurality of longitudinal flat bars 1, 2, 3, 4 arranged in parallel formation and a plurality of lateral 25 spacing braces 5, 6, 7, connecting the same, I provide two parallel marginal rows of bearing rollers 8—8 of hardwood or other suitable material, and a central intermediate row of independent rollers 9, 9 of a smaller 30 diameter than the marginal rollers 8, 8. The rollers are preferably positioned closely adjacent each other to form a substantially continuous roller surface. The rollers 8, 8 are mounted loosely on shafts 10 inserted

35 through the longitudinal bars and positioned above their medial line so that the rollers 8, 8 extend beyond the horizontal plane of the longitudinal bars 1, 2, 3, 4 on one side, and are within the horizontal plane

40 of said rollers on the other side to the end that the rollers 8, 8 will form a roller bearing surface for the device itself when in its normal position and will serve as a roller bearing surface upon which objects may be

45 moved when in an inverted position as shown in Figure 2. It will thus be apparent that when in its normal position the device may be used as a conveyer truck or movable platform and when inverted it will 50 be stationary upon the floor and will serve as an anti-friction conveyer bearing for objects to be moved upon or over it.

I prefer to form the shafts 10 with a head 55 at one end to be seated against the outside face of the device and having an end section 11 projecting within the inner longitudi-

dinal bars 2 and 3 respectively and upon the projecting inner end sections or trunnions 11 are journalled the medial rollers 9. The inner end sections 11 of the shafts 10 are 60 pierced to receive a continuous pin or rod 12 inserted through a plurality of adjacent shafts to retain the shafts in position and to lock the shafts 11 against rotation. It is 65 desirable that the shafts 10 upon which the rollers 8 and 9 turn, be held stationary and that the rollers turn or revolve on the shafts for the reason that this facilitates proper lubrication and prevents friction between the shafts and the longitudinal bars. My 70 device thus assembled will form a truck or conveyer by which objects may be readily moved and when inverted will form a roller surface with a medial longitudinal roller trough or valley extending from end to end 75 of the device for the purpose of guiding toward the centre objects moved upon the device and to overcome the tendency to roll toward the sides and by my improved construction having separate roller sections in 80 the medial trough or valley, I obviate the friction which would result from the use of a single cross roller of varying diameter.

The many uses and advantages of this device are obvious and require no further elucidation and modifications may be made without departing from the spirit of my invention, the novel features of which are more particularly set forth in the claims.

What I claim is:

1. In a device of the character described the combination of a frame comprising a plurality of longitudinal bars arranged in pairs and a plurality of lateral spacing braces, spaced shafts seated in the longitudinal bars and having end sections projecting beyond the inner bar of each pair of bars, rollers mounted loosely on said shafts and a pin engaging a plurality of said shafts to prevent their rotation.

2. In a device of the character described the combination of a frame comprising a plurality of longitudinal bars arranged in pairs and a plurality of lateral spacing braces, spaced shafts seated in the longitudinal bars and having end sections projecting beyond the inner bar of each pair of bars, rollers arranged in parallel rows and carried loosely on said shafts, a pin engaging a plurality of said shafts to prevent rotation thereof and rollers between the inner rows of parallel bars and mounted loosely upon

the projecting ends of the shafts and having a smaller diameter than that of the outer rows of rollers.

3. In a device of the character described, the combination of a plurality of rollers arranged in parallel rows, shafts upon which said rollers rotate and a pin inserted through a plurality of said shafts to lock the same against rotation.

10 4. In a device of the character described,

a frame, a marginal row of loose rollers at the longitudinal sides of said frame, a medial row of loose independent rollers of smaller diameter, shafts carrying the marginal rollers and seated in the medial rollers and a pin inserted through a plurality of adjacent shafts to lock the same against rotation.

In testimony whereof I affix my signature.

JERE L. WENTZ.
